UNITED STATES PATENT OFFICE

2,233,773

FILTER CIRCUIT

Murray G. Crosby, Riverhead, N. Y., assignor to
Radio Corporation of America, a corporation of
Delaware

Original application January 22, 1938, Serial No.
186,273. Divided and this application April 20,
1940, Serial No. 330,656

4 Claims. (Cl. 178—44)

This application which is a division of my United States application Serial No. 186,273 filed January 22, 1938, which issued as U. S. Patent 2,204,574 June 18, 1940, concerns wave filters of the crystal type. The wave filters of the present invention are of wide use in the radio art and involve the use of a piezo-electric crystal in a three-electrode holder connected in circuits arranged to be excited by wave energy of a single frequency or band of frequencies and to pass said wave energy to a plurality of output electrodes in modified form. The output electrodes may comprise two pairs an electrode of each pair in some cases being common.

In describing my invention reference will be made to the attached drawings wherein,

Figures 1, 2 and 3 each show a different modification of my filter circuits. Each embodiment utilizes a piezo-electric crystal in a holder having three electrodes with means for adding to or taking from the reactance between the pairs of electrodes of the holder;

Figures 4a, 4b, 4c and 4f illustrate the characteristics of the filter circuits illustrated in the circuits when arranged and adjusted in accordance with my invention; while

Figures 5a and 5b illustrate the band-pass characteristics of the filters when adjusted in a particular manner described more in detail later.

Wave energy is fed to the primary winding of tuned transformer 100. This transformer is properly damped by resistances 99 and 98 and adjusted by condensers 97 and 96 to form a band-pass filter. The crystal 105 is held in a crystal holder having a single input terminal 101 and two output terminals 102 and 103. The input terminal is connected to the high potential side of the tuned transformer 100 and the two output terminals are connected to the plates 114 and 116 of diodes 109 and 110. Tuned circuits 104, 106, and 107, 108 are connected between the common input terminal and the two output terminals. The resonant frequencies of these tuned circuits are adjusted to be a little above and a little below the resonant frequency of the crystal 105. This slight off-tuning produces an inductive reactance in one case and a capacitive reactance in the other case. Hence the effect will be the same as though a capacity were across one of the sets of crystal terminals and an inductance across the other set. This arrangement causes the formation of two crystal filters having over- and under-neutralized characteristics respectively. Thus, tuned circuit 104, 106 might be

tuned capacitive to present an under-neutralized characteristic such as shown at Figure 4a between transformer 100 and diode 109, and tuned circuit 107, 108 might be tuned inductive to present an over-neutralized filter characteristic such as shown at Figure 4c between transformer 100 and diode 110. In my parent case these characteristics were used to convert phase modulation on wave energy into amplitude modulation on wave energy.

In the circuit of Figure 2 the same principles are applied except that single reactances 106 and 107 take the place of the tuned circuits of the prior figure connected across the crystal holder terminals and diode-driver amplifier tubes 109' and 110' having their grids 113, 115 and cathodes connected to the crystal output electrodes are excited by the filtered energy and are used to feed the two filtered energies to the diodes 109 and 110. Tuned band-pass transformers 128 and 130, having their primaries shunted by damping resistances 125 and 127 couple the anodes and cathodes of the driver tubes 103' and 110' to the diode plates 114 and 116.

In the circuit of Figure 3 a discriminator is shown which utilizes a shunt connected crystal in the manner of the discriminators described in my application #167,344 filed October 5, 1937, now Patent No. 2,156,375 dated May 2, 1939. Intermediate frequency energy is fed to tuned transformer 100' and through isolating resistors 200 and 201 to the two terminals of the crystal holder 102' and 103'. The common terminal 101' of the crystal holder is connected to the low side of the tuned transformer. Reactances X1 and X2 would be either an inductance and a capacity or two tuned circuits. These reactances are adjusted so that one forms a capacitive action across the crystal holder and the other an inductive action. The output of the two filters is taken from terminals 102' and 103' and fed to the grids 113 and 115 of diode-driver tubes 109' and 110' such as are used in Figure 2. The other features of this circuit are the same as those of Figure 1 and Figure 2.

The characteristic of the energy present on the input electrodes of 109 of Figure 1 and in, say, transformer 128 of Figures 2 and 3, is as shown in Figure 4a being derived from a filter of the 50 under-neutralized type such as is obtained by under-neutralizing the holder electrodes 101 and 102 by means of 106 of Figure 2 or the reactance at X1 of Figure 3 or 104 and 106 of Figure 1. This is obtained by adjusting the said elements 55

of the respective filters so that the reactance across the crystal holder is capacitive for the case of the series connected crystals of Figures 1 and 2 and inductive for the case of the shunt connected crystals of Figure 3. The characteristic of the energy, say in transformer 130 of Figures 2 and 3, or on the electrodes of diode 110 of Figure 1 is as shown in Figure 4e, this energy being passed by filters which are over-neutralized by adjusting the elements 107 and 108 of Figure 1 or 107 of Figure 2 so that the crystal holder has an inductive reactance at substantially the carrier frequency, and adjusting the reactance X2 of Figure 3 so that the crystal holder has a capacitive reactance. In the case of the shunt connected crystal, the under-neutralized characteristic is given by Figure 4e and its reactance characteristic is given by Figure 4b. That is, in the case of the shunt connected filter the low impedance point on the reactance curve (where the line crosses the X axis) coincides with the rejection point on the output characteristic. Also, the high impedance point on the reactance curve coincides with the carrier frequency. This is opposite to the case of the series connected filter in which the under-neutralized characteristic is given by Figure 4a, its reactance curve is given by 4b, the zero reactance curve coincides with the carrier frequency, and the maximum impedance point coincides with the rejection point.

The reason for this difference between the shunt and series connected filters is the fact that with the series connection the crystal allows more or less energy to flow according to its impedance, while with the shunt connection, since the drop across the crystal is utilized, the output voltage is proportional to the crystal impedance.

40 In the case of Figure 4b a negative reactance is present on both sides of the carrier frequency, that is, the circuit would be capacitive on both sides of the carrier except for the very short interval near the carrier frequency.

45 I have found that by adjusting the crystal filters so that one has a very small amount of negative reactance across the holder and the other a very small amount of positive reactance, a single sideband effect is obtained as shown in Figures 5a and 5b. With the crystals almost neutralized in this way the output on the side of the carrier frequency which does not have the rejection point is higher than the output on the side having the rejection point. Consequently, 50 one of the filters exalts the carrier and selects the lower sideband and the other exalts the carrier and selects the upper sideband.

For more detailed description of the characteristics and adjustments of my filter circuit

and for the various uses to which the same may be put, reference is made to the parent application Serial No. 186,273 filed January 22, 1938 (Patent 2,204,574).

What is claimed is:

5 1. In a wave filtering system, an impedance on which wave energy to be filtered may be impressed, an output circuit, a piezo-electric crystal having three electrodes, means connecting a pair of said electrodes and said impedance in a 10 first filter circuit coupled to said output circuit, means connecting a second pair of said electrodes and said impedance in a second filter circuit coupled to said output circuit and reactances connected in shunt to each of said pair of crystal 15 electrodes, to supplement the reactance between both pairs of electrodes.

2. In a wave filtering system, an impedance on which wave energy to be filtered may be impressed, an output circuit, a piezo-electric crystal 20 having three electrodes, means connecting a pair of said electrodes and said impedance in series in a first filter circuit coupled to said output circuit, means connecting a second pair of said electrodes and said impedance in series in 25 a second filter circuit coupled to said output circuit and reactances connected in shunt to each of said pair of crystal electrodes, to supplement the reactance between both pairs of electrodes.

3. In a filter circuit, an impedance on which 30 wave energy to be filtered may be impressed, an output circuit, a piezo-electric crystal having three electrodes, means connecting a pair of said electrodes and said impedance in a first filter circuit coupled to said output circuit, means connecting a second pair of said electrodes and said impedance in a second filter circuit coupled to said output circuit, a reactance connected in shunt to one of said pair of electrodes, of a nature 35 such that the reactive effect of the crystal electrodes is inductive, and a reactance connected in shunt to the other pair of said electrodes of a nature such that the reactive effect of the crystal electrodes is capacitive.

4. In a filter circuit, an impedance on which 40 wave energy to be filtered may be impressed, an output circuit, a piezo-electric crystal having three electrodes, means connecting a pair of said electrodes and said impedance in a first filter circuit coupled in shunt to said output circuit, 45 means connecting a second pair of said electrodes and said impedance in a second filter circuit coupled in shunt to said output circuit, a reactance connected in shunt to one of said pair of electrodes, of a nature such that the reactive effect is inductive, and a reactance connected in shunt to the other pair of said electrodes of a nature 50 such that the reactive effect is capacitive.

MURRAY G. CROSBY.
